PIVOTABLE BOLT LATCH

Lawrence D. Smith, Pacoima, and Franklin L. Sawyer, Canoga Park, Calif., assignors to Clark Hartwell, doing business as Hartwell Aviation Supply Company, Los Angeles, Calif.

Application June 14, 1957, Serial No. 665,767

3 Claims. (Cl. 292—196)

This invention relates to pivotable bolt latches, and included in the objects of this invention are:

First, to provide a latch which is primarily intended for doors or access panels flush with surrounding structure, and has particular application to such panels or doors provided in aircraft.

Second, to provide a latch wherein an essentially J-shaped latch arm is movable between an extended and a retracted position by overcenter link elements and a handle member so arranged that the latch arm may be locked in its extended position and loads imposed thereon cannot exert releasing forces on the link elements and handle member.

Third, to provide a latch of this type wherein the handle lever may be mounted flush with the surrounding structure, and both an auxiliary latch and a separate fastener means are employed to retain the handle in its flush position so that the possibility of accidental release is extremely remote.

Fourth, to provide a latch of this type wherein the latching position of the latch arm may be accurately adjusted, and in so doing the door or panel in which the latch is mounted may be brought into exactly flush relation with the surrounding structure.

With the above and other objects in view, as may appear hereinafter, reference is directed to the accompanying drawings in which:

Figure 1 is a top or plan view of the latch, the parts being in the position assumed when the latch is closed;

Fig. 2 is an enlarged longitudinal sectional view through 2—2 of Fig. 1, showing the latch in its closed position and in engagement with a keeper member, and also indicating by broken lines and fragmentarily the structures in which the latch and its keeper are mounted;

Fig. 3 is a view similar to Fig. 2 showing the latch in its open position, but omitting the surrounding structure and keeper member;

Figs. 4 and 5 are transverse sectional views through 4—4 and 5—5, respectively, of Fig. 2.

The latch structure includes a pair of side plates 1 which are roughly rhombic in shape. The two acute corners of the side plates are provided with connecting sleeves 3 and 4 through which extend mounting bolts 5 and 6. The mounting bolts are secured to suitable brackets or to a frame, not shown.

Journalized on the sleeve 3 is a bolt lever 7 which is substantially J-shaped. The pivotal axis of the lever is at the end of its longer leg, whereas the shorter leg is provided with a shoe 8 having lugs which fit over the sides of the lever and are connected thereto by a pin 9. The extremity of the lever is relieved slightly under the shoe 8 to permit limited pivotal movement of the shoe about the axis of the pin 9.

The bolt lever 7, when in its extended position, is adapted to engage a suitable keeper bracket 10 supported on a structure A, which may be a portion of the frame in which a door or panel B, with which the side plates 1 are connected, is intended to fit.

2

Pivottably mounted on the sleeve 4 is a link member 11 having an extended socket end 12 which is internally screw-threaded. The socket end 12 receives a differential screw 13 which is provided with a screw-threaded bore to receive a screw shaft 14. The pitch of the screw threads joining the differential screw 13 with the link member 11 is greater than the pitch of the screw threads joining the differential screw to the screw shaft 14. Thus by rotating the differential screw while the screw shaft

14 and link member 11 are restrained from turning causes the screw shaft 14 to extend or retract, and, depending on the selection of the relative pitches of the screw threads, an adjustment of the desired preciseness may be attained. Or, if desired, right and left pitch screw threads may be used so that a coarse adjustment which is the sum of the screw threads may be obtained.

The protruding end of the differential screw 13 is provided with a slotted flange 15 to facilitate rotation. A U-shaped spring retainer 16 fits over the end of the link member 11 and is provided with a spring leg which engages the slots of the flange 15 to secure the differential screw 13 in various adjusted positions.

The extended end of the screw shaft 14 terminates in an eyelet in which is fitted a transverse pin 17. The pin 17 journals a pair of link bars 18, the extended ends of which are pivotally connected by a pin 19 to the bolt lever 7 near the root end of its pivoted leg.

Between the lower obtuse corner defined by the side plates 1, under the link bars 18, is a stop pin 20 which is engaged by the link bars 18. The under side of the link bars 18 are provided with arcuate recesses 21. The location of the stop pin 20 and the arrangement of the recesses 21 are such as to permit slightly overcenter positioning of the axis of the pin 17 relative to the plane defined by the axis of the pin 19 and the axis of the sleeve 4. By appropriate shaping of the recesses 21 this overcenter position is maintained within the limits of extension and retraction of the screw shaft 14. When the link bars 18 engage the stop pin 20, the bolt lever 7 is in its keeper bracket-engaging position. Any loads which may be applied to the shoe 8 are transmitted to the two mounting bolts 5 and 6 with only a relatively small force component on the stop pin 20. Thus the bolt lever 7 is rigidly locked when in its extended position.

45 A handle lever 22 is provided. The handle lever is preferably formed of sheet metal and is channel-shaped in cross section, forming a web 23 and parallel side flanges 24. A journal pin 25 extends between the side flanges 24 and through the side plates 1 near the mounting bolt 5. The handle lever 22 extends in a direction 50 away from the mounting bolt 5 and above the mounting bolt 6, and terminates beyond the side plates 1. The web 23 is intended to be positioned flush with the door or panel, or other structure, B in which the latch is mounted. 55 The free extremity of the web 23 is provided with fastener-receiving hole 26 for securing this end to the structure B.

Near the journal pin 25 the side flanges 24 are provided with lost motion slots 27 which receive a transverse pin 28. The pin 28 journals a pair of link members 29 which extend downwardly and are joined to the journal pin 17. Upon rotation of the handle lever 22 about its axis, the link members 29 draw upwardly on the pin 17 causing the link member 11 and link bars 18 to fold and draw the bolt lever 7 towards its retracted position, as shown in Fig. 3.

The lost motion slots 27 permit limited initial movement of the handle lever 22. A spring 30 is wrapped around the journal pin 25 and bears between the pin 28 and web 23 so that the handle lever 22 tends to spring upwardly from the structure B through an arc deter-

mined by the lost motion slots 27. This free movement places the handle member 22 so that it may be readily grasped.

In addition to the fastening means which utilizes the screw hole 26, the handle lever 22 may be held in its flush position by means of an auxiliary latch member 31. The latch member 31 is formed of sheet material and is channel-shaped in cross section, forming a web 32 and parallel side flanges 33. The web 23 of the handle lever 22 is provided with an aperture 34 which receives the web 32 so that the web 32 may be flush with the web 23.

The auxiliary latch member 31 is pivoted relative to the handle lever 22 by means of a journal pin 35 extending between the side flanges 33 and side flanges 24. A spring 36 is wrapped about the journal pin 35. One end of the spring engages an anchor pin 37 whereas the other end bears against the web 32 to urge the auxiliary latch member 31 into its flush position. Extensions of the side flanges 33 form stops 38 which engage under the web 23 adjacent one end of the aperture 34.

The side flanges 33 project downward and terminate in hook elements 39 which engage a keeper pin 40 disposed between upwardly projecting bosses 41 located above the mounting bolt 6. The side flanges 33 above the hook elements may form cams 33a which on pivoting of the auxiliary latch raise the handle lever 22, and thus eliminate the need of the spring 30.

Operation of the latch structure is as follows:

When the latch is in its closed or operating position, the bolt lever 7 is extended with the shoe 8 in engagement with the keeper bracket 10. The axis of the pin 17 is slightly below the plane defined by the mounting bolt 6 and pin 19 so that the link bars 18 bear against the stop pin 20. The handle lever 22 is in its flush position relative to the surrounding structure B and may be secured thereto by suitable means extending through the hole 26. In addition the auxiliary latch member 31 is in its flush position relative to the handle lever 22 and the hook elements 39 are in engagement with the keeper pin 40.

When it is desired to open the latch, the retaining means in the hole 26 is removed or released and the auxiliary latch member 31 is manually pivoted by pushing inward on the appropriate end of the web 32, whereupon the spring 30 causes limited initial movement of the handle lever 22 so that it may be manually grasped for further movement. Further rotation of the handle lever 22 moves the handle lever to the position shown in Fig. 3. This movement causes the link members 29 to draw upwardly on the pin 17, jackknifing the link member 11 and link bars 18, so as to pivot the bolt lever 7 to its retracted position, as shown in Fig. 3.

It is essential that the upper surface of the structure B be flush with the structure A. Leveling or adjustment of the structure B is accomplished by extending or retracting the screw shaft 14, which alters the latching position of the bolt lever 7 so that the structure B may be raised or lowered relative to the structure A, as viewed in Fig. 2, until the two structures are exactly flush.

While a particular embodiment of this invention has been shown and described, it is not intended to limit the same to the exact details of the construction set forth, and it embraces such changes, modifications, and equivalents of the parts and their formation and arrangement as come within the purview of the appended claims.

What is claimed is:

1. A latch construction, comprising: an essentially J-

shaped latch lever pivotally mounted at the extremity of its longer leg and having a latch face at the extremity of its shorter leg; a pair of tandem-disposed link units pivotally joined to each other for relative movement about an intermediate axis, one of said link units being pivotally joined to said latch lever, the other link unit having a remote pivotal axis; a link means connected to said link units for moving said intermediate pivotal connection laterally, thereby to pivot said latch lever between an extended latching position and a retracted position; means incorporated in one of said link units for adjusting the effective length thereof, thereby to alter the location of the latching position of the latch lever; a handle lever pivotally mounted by one end; a lost motion connection between said handle lever and said link means to permit limited free movement of said handle lever, said handle lever being operable to move said link means thereby to effect movement of said latch lever; and an auxiliary latch member carried by said handle lever including hook means, and an auxiliary keeper engageable by said hook means.

2. A latch construction, comprising: a pair of side plates; a latch lever pivotally mounted therebetween; a pair of tandem-disposed link units pivotally joined to each other about an intermediate axis, one of said link units being pivotally connected to said latch lever about one extreme axis, the remote end of the other link unit being pivotally connected between said side plates about the other extreme axis; a laterally directed link means joined to said link elements for displacing said intermediate axis laterally between said extreme axes, thereby to effect pivotal movement of said latch lever between an extended latching position and a retracted position; a handle lever also pivotally mounted by one end between said side plates; and a lost motion connection between said handle lever and said link means to permit limited free movement of said handle lever, said handle lever being operable to move said link means thereby to effect movement of said latch lever.

3. A latch construction, comprising: a pair of side plates; a latch lever pivotally mounted therebetween; a pair of tandem-disposed link units pivotally joined to each other about an intermediate axis, one of said link units being pivotally connected to said latch lever about one extreme axis, the remote end of the other link unit being pivotally connected between said side plates about the other extreme axis; a laterally directed link means joined to said link elements for displacing said intermediate axis laterally between said extreme axes, thereby to effect pivotal movement of said latch lever between an extended latching position and a retracted position; a handle lever also pivotally mounted by one end between said side plates; a lost motion connection between said handle lever and said link means to permit limited free movement of said handle lever, said handle lever being operable to move said link means thereby to effect movement of said latch lever; and an auxiliary latch member carried by said handle lever including hook means, and an auxiliary keeper carried by said side plates engageable by said hook means.
